UNITED STATES PATENT OFFICE.

EDGAR RICHARD WATERMAN, OF HELENA, MONTANA.

OIL-BURNER.

SPECIFICATION forming part of Letters Patent No. 715,912, dated December 16, 1902.

Application filed November 11, 1901. Serial No. 81,912. (No model.)

To all whom it may concern:

Be it known that I, EDGAR RICHARD WATERMAN, a citizen of the United States, residing at Helena, in the county of Lewis and 5 Clarke and State of Montana, have invented a new and useful Oil-Burner, of which the following is a specification.

My invention is an improved oil-burner especially adapted for use as an attachment 10 for ordinary cooking-stoves, ranges, and heaters, and to burn oil, either crude, refined, or distillate; and it consists in the peculiar construction and combination of devices herein- 15 after fully set forth and claimed.

15 In the accompanying drawings, Figure 1 is a perspective view of my improved oil-burner, showing the same as an attachment to an ordinary cooking-stove. Fig. 2 is a top plan view showing the top plate of my improved 20 burner. Fig. 3 is a vertical sectional view of my improved burner, taken on a plane indicated by the line *a a* of Fig. 2. Fig. 4 is a top plan view showing the bottom plate and the generating-cone formed thereon. Fig. 5 25 is a detail elevation of the clamp for connecting my improved oil-burning attachment to a stove. Fig. 6 is a detail perspective view. Fig. 7 is a detail sectional view showing the profiles of the generating-cone and the flared 30 opening in the top plate. Figs. 8, 9, 10, and 11 illustrate modifications of my improved burner.

35 In the embodiment of my invention I provide a top plate 1, which is preferably circular in form and is adapted to be substituted for one of the removable lids of an ordinary cooking or heating stove or range. As here shown, the said top plate is provided on its under side with an annular rabbet 2 of such 40 width that the top plate is adapted to be used on stoves of various sizes, the said rabbet adapting the top plate to be placed in or on a stove-lid opening of any size. The said top plate is provided with a feed-pipe 3, which 45 extends from a reservoir 4 to contain the oil. The end of the feed-pipe 3, where the same is connected to the top plate, is bent upwardly and then downwardly to form a siphon or gooseneck 5, and the said pipe is preferably 50 provided with a valve 6 to cut off or permit the flow of oil. Owing to the curvature 5 in the said pipe 3, the supply of oil to the burner

ceases as soon as the valve 6 is closed, as will be understood. The inner end of the feed-pipe 3 is connected to an opening 7 in the top 55 plate 1 at a suitable distance from one side of the latter, and near and on opposite sides of the said opening 7 are air-inlet openings 8, which may be of any suitable form, but are preferably of the form shown in Fig. 2. I 50 also provide a bottom plate 9, which is preferably of the form shown in Figs. 3 and 4 and has its upper side dished or concaved, as at 10. The said bottom plate is formed with hangers 11 on its upper side, which are ap- 65 proximately of conical form and the upper ends of which are adapted to enter recesses in the lower side of the top plate 1. Screws 12 or other suitable devices are employed to secure the said hangers to the under side of 70 the top plate, and thereby connect the bottom plate thereto in such manner that the bottom plate may be readily removed from the top plate when desired. On the upper side of the bottom plate, at a point immediately under 75 the opening 7, is a generating-cone 13, which is formed integrally with the bottom plate and is truncated, as shown. The upper portion of the said generating-cone is disposed in a down- 80 wardly-flared opening 14, with which the top plate 1 is provided, which opening 14 forms an extension or lower continuation of the said opening 7, and it will be observed by reference to Fig. 3 of the drawings that a slight annular channel 15 is formed between 85 the said flared opening 14 and the upper portion of the said generating-cone. The latter is provided with radially-disposed grooves 16, which are formed on its surface and extend from the base thereof to its apex and 90 serve to conduct the oil from the pipe 3 down- 95 wardly on the said generating-cone toward the bottom plate.

In operation when my improved oil-burner is in use as an attachment to a stove air is 95 drawn downwardly through the openings 8 in the top plate, which openings, being disposed near opposite sides of the generating-cone, cause the air to unite with the vapors or gases from the oil and cause the same to be con- 100 sumed. It will be understood that owing to the heated condition of the parts of the burner the oil, which is supplied to the apex of the generating-cone, is converted into

gases or vapors while passing downwardly in the channel 16 of said generating-cone, and hence the oil is entirely consumed as it is fed to the burner. The concaved or dished upper side of the bottom plate adapts the same to hold a small quantity of oil, to be ignited for the purpose of initially heating the burner before the same is started in operation.

My improved burner is adapted for burning crude oil as well as refined or distillate oil, and in the practical operation of my burner I find that the same does not become clogged with carbonaceous residues, and hence does not require to be cleaned and requires practically no attention when in operation.

An annular plate 17, provided on its under side with radially-disposed downwardly-extending tongues 18, is adapted to be placed around the generating-cone and to rest on the bottom plate at the base of said cone for use in summer.

The base of the generating-cone is hollowed, as at 19.

Owing to the fact that the air which becomes carbureted and consumed by the burner is supplied to the same through the openings 8 in the top plate when my improved burner attachment is in use in connection with a stove or range, the burner is entirely unaffected by outside drafts, no matter in what position the stove may be placed or to what drafts it may be exposed, and hence there is no danger of the flame becoming extinguished and the burner becoming "flushed" by the escape without the consumption of the oil. Furthermore, all odors incident to the burning of the oil are confined to the interior of the stove and the flue, and none of the odors escape and become offensive in the room in which the stove is located.

In connection with my improved oil-burning attachment I provide a clamp, which is shown in Fig. 5, for supporting the feed-pipe 3 and the reservoir and enabling my improved burner attachment to be readily attached to or removed from an ordinary stove. The said clamp comprises an outer section 20, an inner section 21, and a set-screw 22, which connects the same together. The outer section 20 is of approximately semicircular form and has a pair of upwardly-extending jaws 23 24. The latter is wider than the former and is provided with a semicircular, preferably serrated, recess 25. The said inner section 21 is formed on one side with a hook 26, which overhangs the recess 25 and the lower side of which is correspondingly curved and serrated, as at 27. The opposite side of the upper portion of said inner section 21 is formed with a jaw 28, which somewhat overhangs the upper end of the jaw 23. The feed-pipe 3 is disposed in the recessed opposing sides of the jaws 24 26, the flange of the stove being engaged by and between the jaws 23 28, and by tightening the set-screw 22 the said clamp may be thus readily attached to the stove in

position to support the feed-pipe 3 and the reservoir, as will be readily understood. Furthermore, by slightly loosening the set-screw 22, so as not to disengage the clamp from the flange of the stove-top, the feed-pipe 3 will be turned axially in the recesses 25 27 of the jaws 24 26 to enable my burner attachment to be raised from the stove-opening in which it has been disposed and turned to one side of the stove-top, as will be understood from an inspection of Fig. 1. The set-screw is here shown as provided with a winged head to enable it to be readily turned by the thumb and forefinger. The outer section 20 has a slot 20^a, in which the shank of the set-screw operates, thus enabling the section 21 to be adjusted laterally, as may be required in the operation of the clamp.

By the use of the annular plate 17, which, as before stated, is designed for summer use, the effective superficial area of the cone may be diminished, as said plate when seated on the base of the cone has the effect of reducing the height of the latter. Hence the size of the flame produced by the action of the burner is diminished when the plate 17 is used. Furthermore, the use of the said plate 17 enables the burner to be more readily started in operation, as said plate becomes initially heated very quickly. Said plate also acts as a deflector or spreader.

In Figs. 8 and 9 of the drawings I show a modified form of my invention especially adapted for use for heating purposes in connection with heating-stoves, furnaces, and small boilers. In this form of my invention the door A of the stove or furnace forms the body of the burner and is cast with a box B, which projects from the outer side thereof, and the bottom of which box forms the bottom plate or support for the cone or cones, of which any suitable number may be used. The top or cover C of the box has an outwardly-projecting flange D at its outer side. The clamps which secure the feed-pipe 3 engage said flange. Said top or cover also has the draft-inlet openings 8 formed therein. In this form of my invention the reservoir 4, as well as the pipe 3, may be supported by the clamps, or the reservoir may be provided on one side with a vertically-disposed strip E, projecting above and below the reservoir and having a circular opening e in its lower projection and an opening e', enlarged at its lower side, in its upper projection, to enable the reservoir to be supported on a wall or partition of a room by headed nails or screws. In Figs. 11 and 10 of the drawings I show, respectively, a boiler-furnace and a range provided with a door, in which my improved burner is included.

Having thus described my invention, I claim—

1. A burner of the class described, comprising a top plate; a feed-pipe discharging through an opening therein; said top plate being further provided with air-inlet open-

ings; and a bottom plate, suspended below and supported by the top plate, concaved on its upper side and having a generating-cone disposed with its apex under the discharge 5 of the feed-pipe, substantially as described.

2. In a burner of the class described, a top plate having an opening through which oil is fed, and a flared downwardly-extending prolongation of said opening; in combination 10 with a generating-cone having its apex disposed in the flared prolongation of said feed-opening, substantially as described.

3. A burner of the class described, comprising a top plate; a feed-pipe discharging 15 through an opening therein; said top plate being further provided with air-inlet openings; and a bottom plate, suspended below and supported by the top plate and having a generating-cone disposed with its apex under 20 the discharge of the feed-pipe, substantially as described.

4. A burner of the class described, comprising a top plate; a feed-pipe discharging through an opening therein; said top plate 25 being further provided with air-inlet openings; and a bottom plate having a generating-cone disposed with its apex under the discharge of the feed-pipe; said cone having channels on its surface to conduct oil from 30 its apex to its base, substantially as described.

5. A clamp for the purpose set forth, comprising an outer section; an inner section; and an adjusting-screw connecting the said sections; the latter being formed with clamping-jaws to engage the flange of a stove-top 35 and a pipe, to connect the latter to the stove-top, substantially as described.

6. In a burner of the class described, a top plate having an oil-feed opening, a generating-cone having its apex disposed in and surrounded by said opening, and means to admit air to the exterior of the cone, substantially as described. 40

7. In a burner of the class described, a bottom plate, concaved on its upper side and 45 having a generating-cone with its base on said plate, means to feed oil onto the apex of the cone, and an annular plate 17 disposed around the base of the cone and having the flanges 18 on its under side bearing on the 50 surface of the bottom plate from which the cone rises, said plate 17 being detachable from the cone, substantially as described.

In testimony that I claim the foregoing as my own I have hereto affixed my signature in 55 the presence of two witnesses.
